(57) **CLAIM**

The ornamental design for a shelf, as shown and described.

DESCRIPTION

FIG. 1 is a first perspective view of a shelf showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the shelf thereof;

FIG. 10 is another exploded view thereof;

FIG. 11 is an enlarged view of the selected portion 11 in FIG. 1;

FIG. 12 is an enlarged view of the selected portion 12 in FIG. 10; and,

FIG. 13 is an enlarged view of the selected portion 13 in FIG. 10.

The dash-dash broken lines shown in the drawings depict portions of the shelf that form no part of the claimed design. The dot-dash broken lines in FIGS. 1, 10, 11, 12 and 13 illustrate the periphery of the enlarged views of the shelf and form no part of the claimed design.
